(57) **CLAIM**

The ornamental design of a pump housing as shown and described.

DESCRIPTION

FIG. 1 is a front perspective view, observed from the right front side, of a pump housing according to the present invention.

FIG. 2 is a front elevational view of the pump housing of FIG. 1.

FIG. 3 is a rear elevational view of the pump housing of FIG. 1.

FIG. 4 is a right side elevational view of the pump housing of FIG. 1.

FIG. 5 is a left side elevational view of the pump housing of FIG. 1.

FIG. 6 is a top plan view of the pump housing of FIG. 1; and, FIG. 7 is a bottom plan view of the pump housing of FIG. 1.

The broken lines in the drawings are for the purpose of illustrating portions of the pump housing that form no part of the claimed design.

1 Claim, 7 Drawing Sheets
